United States Patent Office.

JAMES D. HATHAWAY, OF MEDFORD, MASSACHUSETTS.

Letters Patent No. 66,332, dated July 2, 1867.

IMPROVED SCREW-CLAMP FOR PLANKING VESSELS.

The Schedule referred to in these Letters Patent and making part of the same.

TO ALL WHOM IT MAY CONCERN:

Be it known that I, JAMES D. HATHAWAY, of Medford, in the county of Middlesex, and Commonwealth of Massachusetts, have invented a new and improved Screw-Clamp for Planking Vessels; and I do hereby declare the following to be a full and exact description thereof, reference being had to the accompanying drawings, and to the letters of reference marked thereon, in which—

Figure 1 is a side view of the instrument.

Figure 2 is an edge view of the same.

The nature of my invention consists in so constructing the screw-clamp that, when used in planking a vessel which is sealed up on the inside, one end, *a*, of the clamp may be inserted between the knees or timbers of the vessel, and held there firmly by means of the serrated cam *b*, attached to one end of the clamp, while the other end comes out over the plank to be brought and held in position to be fastened to the outside of the timbers.

To enable others skilled in the art to make and use my invention, I will proceed to describe its construction and operation.

I make the clamp-frame *c* of any desired shape and strength. I then attach to the shorter end *d* of the frame *c* a serrated cam, *b*, having a perforation near its smaller end fitted to go on and turn upon said shorter end *d* of the frame *c*, prepared for that purpose as an axle. The axle may be provided with a nut and screw to hold the cam *b* in its place, or it may be headed down to hold it as in the drawings. The advantage of the nut and screw is to facilitate the exchange of one cam for another when the timbers are different distances apart and require cams of different sizes. I construct the cam in the ordinary way, but make its axis of revolution nearer the smaller end, and cut teeth *e* in the larger end opposite its axis of revolution. In the other or longer end of frame *c* is cut a female screw, *f*, into which is fitted the male screw *g*, to the inner end of which is attached a head or cap, *h*, so made as to allow the screw *g* to be turned, when the cap is placed against any substance, without the cap itself revolving. The outer end of screw *g* is provided with a suitable handle, *i*, for turning the screw.

By inserting the end of the clamp having the cam attached between the knees or timbers of the vessel, the teeth *e* fix into one timber, and the smaller end braces against the opposite timber, so that when power is applied to draw it outward it takes fast hold, and becomes more firmly attached the greater the power applied. The cap *h* of the male screw *g* is then brought to bear upon the plank to be attached to the outside of the timbers, and by turning the screw *g* it is brought up against the timbers and held there until fastened.

I am aware that screw-clamps have been in use for a long time. Mine differs from them in construction.

I do not claim the screw-clamp patented to Abram Perrin April 5, 1864; but I claim, and desire to secure by Letters Patent—

A screw-clamp, consisting of a frame, a male and female screw, and a serrated cam, combined and operating substantially as described.

JAMES D. HATHAWAY.
